UNITED STATES PATENT OFFICE.

HANS PFAFFENBERGER, OF NUERMBERG, GERMANY.

TOY VEHICLE.

Application filed March 31, 1927, Serial No. 179,976, and in Germany April 10, 1926.

This invention has for its object to create a toy-vehicle, the character of which may be altered by exchanging building elements, this exchanging being easy to carry out.

- 5 A transformable toy-vehicle, adapted to be transformed by interchanging the carriage-body on a stationary chassis has become known. In toy-vehicles of this type it is possible to change a toy vehicle running on roads into another toy vehicle running on roads and a toy vehicle running on rails into another toy-vehicle running on rails. It is however not possible to transform a toy-vehicle running on rails into a toy-vehicle 10 running on roads and inversely, i. e. the two types of toy-vehicles cannot be interchanged.

This advantage is obtained by the present invention.

- 20 On an under-frame, common for the two types of toy-vehicles, the interchangeable elements, as sets of wheels and carriage-bodies of the type of vehicles or of the vehicle, are removably mounted so that the same under-frame can be used in connection with sets of wheels and carriage bodies of any of the two types of toy-vehicles. For mounting the sets of wheels in position, two pairs of vertical slots for the insertion of the 25 wheel-axes, are provided in the longitudinal flanges of an under-frame, adapted for all vehicles and carrying a driving spring mechanism, said slots being arranged at different distances and at different heights, 30 open at the lower ends, and forming at the top end each one half of an axle bearing, the longitudinal flanges of a slidable plate guided in this under-frame having two pairs of angular slots, which when the slidable 35 plate is shifted accordingly, are adjusted for interchanging the sets of wheels, so that their vertical arms register with the slots of the flanges of the under-frame. For locking the inserted wheel-axes the sliding plate 40 is shifted in opposite direction so that the lower edges of the horizontal arms of said angular slots bear from below under the wheel axles. In this manner it is possible to rapidly interchange and lock into their 45 position two different sets of wheels which comprise different wheels, said wheels being differently spaced according to whether they belong to a vehicle running on roads or to a vehicle running on rails. The under-frame of a vehicle running on roads can

therefore be used also for a vehicle running on rails and inversely.

For completing the transformation the interchanging of the upper structures on the under-frame for the corresponding types 60 of toy-vehicles must be adapted to be rapidly carried out. According to the invention this rapid exchanging is rendered possible as each of the upper structures forms an elastic snapping element or carries elastic elements which, when the upper structure is pressed from above upon the under-frame 65 engage under the edge of the platform of the under-frame and give way elastically when the upper structure is suddenly pulled 70 off.

An embodiment of the new transformation toy-vehicle is illustrated, by way of example, in the accompanying drawing, in which

75 Fig. 1 shows the under-frame,

Fig. 2 the slidable locking plate,

Fig. 3 these elements united in the position in which the wheel axles are locked and further the seat of a bottom-plate of a carriage body. These three figures are all shown in longitudinal section on line A—B of Fig. 4.

Fig. 4 shows in plan view, seen from below, the under-frame.

80 Fig. 5 is a cross section on line C—D,

Fig. 6 is a cross section on line E—F,

Fig. 7 a cross section on line G—H of Fig. 3.

Fig. 8 shows, as example for a toy-vehicle 90 running on rails, a locomotive and

Fig. 9 as example of a toy-vehicle running on roads, a motor car, which may be combined selectively.

The platform *a* of the under-frame carries a spring-driving mechanism *b*, the extreme driving wheel *c* of which is designed to drive a pinion *f* keyed on the driving wheel-axle *d*. In the longitudinal flanges *g* of the under-frame two pairs of vertical slots *h* and *i* are arranged which are open at the bottom end and form at their top ends each one half of an axle bearing *k*. The slots *h* are arranged lower down and closer together than the slots *i*. The slots *h* are designed to receive the axles *l*, on which the running wheels *m* for vehicles running on rails are mounted at a shorter distance the one from the other and of a smaller diameter.

The slots *i* serve to receive the axles *d*, the running wheels *n* which are designed to run on roads, having a greater diameter and they are mounted at a greater distance the one from the other.

In this under-frame a slideable-plate *o*, *p* is guided. Two flaps *q* serving as handles are cut out of the top-plate *o* of this slideable plate.

10 In the longitudinal flanges *p* of this slideable plate angular slots *r*, *s* and *t*, *u* are arranged. The vertical arms of the slots *r* are spaced at a distance equal to that of the slots *h*. The distance between the vertical arms *t* of the slots *t*, *u* is equal to that between the slots *i*. The arms *r* of the slots can be made to register with the slots *h* and the arms *t* of the slots can be made to register with the slots *i*. When the slots are in 15 the registering position the child can insert or remove the running wheel-axles. When, the axles being inserted, the handle *q* of the slideable plate is pulled to the rear into the position shown in Fig. 3, the lower edges *v* 20 of the horizontal arms *s*, *u*, i. e. the locking noses *w*, are pushed under the axles which are thus locked in the under-frame and can be lifted with the frame from the floor, table or other support. The shifting of the 25 slideable plate to the rear, and for removing the axles the shifting to the front, are limited by flanges *x* bent downward from the short sides of the platform *a*. Holding flaps *y* grip from below over the middle of 30 the lower edges of the slideable plate.

As example of a carriage body for a vehicle running on roads to be mounted on the under-frame *a*, *g*, a motor car-body 3 with engine-bonnet 4, foot-board 5 and wheel-guards 6 is shown on the drawing. A boiler 7 with engineer's cabin 8 is shown as example for the body of a vehicle running on rails. Any other types of the body for vehicles running on roads or on rails may however be used. According to the invention each of these carriage bodies is mounted on a base-plate 9 which has elastic downwardly directed flaps 10 at the short sides and downwardly turned flanges 10' on the long 45 sides and gripping over the long sides of the platform *a* of the under-frame. Bosses 11 on the inner surfaces of the end flaps 10 slip, when the carriage-body is strongly pressed upon the platform *a*, along the end flanges *x* of this platform to snap in under the lower end of said flaps. The carriage-body is thus fixed well enough on the under-frame so that the whole vehicle can be lifted by gripping the carriage-body.

50 To remove the carriage-body it is only necessary to pull it away from the under-frame by holding this under-frame with the other hand. As the end-flaps 10 are elastic, the bosses 11 give way.

55 The manipulations which the child has to

carry out to transform a toy vehicle running on roads, shown in Fig. 9, into a toy-vehicle running on rails, shown in Fig. 8, are very simple. The carriage body 3, 4 has to be pulled off with a jerk, the slideable plate 70 has to be pushed forward with the aid of the handle *q* until it strikes against the downwardly turned flange *x* at the front end and the sets of wheels *n*, *d* are removed, whereupon the axles of the sets of wheels 75 *m*, *l* for a vehicle running on rails are inserted into the slots *h*, *r* to be locked in this position by pulling back the slideable plate up to the rear-end flange *x*, the carriage-body 7, 8 being then placed and pressed upon the 80 platform *a*. Although the slideable plate with the locking noses *w* forms the simplest manner of locking the inserted wheel-axles, other locking means may be used without departing from the general idea of the invention. The bosses 11 might be made to engage under other edges of the platform of the under-frame as under the bottom edges of the front flaps. The main characteristic of the invention is the possibility to put together toy-vehicles not only of the several 85 elements belonging to one of the two types of toy-vehicles i. e. toy-vehicles running on rails and toy vehicles running on roads but also the transformation of a toy-vehicle of 90 one type into a toy-vehicle of the other type by using the same under-frame for vehicles 95 of any type.

I claim:—

1. An under-frame for toy vehicles running on roads and for toy vehicles running on rails, a downwardly directed flange on each long side of said under-frame said flange having two pairs of slots upwardly extending from the lower edge of said flange and forming at the upper end one half of an axle bearing the slots of the one pair being spaced at other distance and being of other height than the slots of the other pair, a slideable plate on said under-frame, a downwardly directed flange on each long side of said plate said flanges having each two pairs of angular slots open at the lower end each slot composed of a vertical arm and of an upper horizontal arm forming together a locking nose the vertical arms of said slots being spaced at the same distance and being of the same height as the vertical arm of the corresponding slots in said flanges of said under-frame, said under-frame and slideable plate adapted to combine selectively with either one of a plurality of sets of wheels to represent the wheel sets for vehicles running on roads or on rails said sets of wheels being locked in position by the noses of the corresponding slots, and with either one of a plurality of carriage bodies to represent any kind of vehicles running on roads or on rails, and means for securely holding a carriage body on said under-frame.

2. An under-frame for toy vehicles running on roads and for toy vehicles running on rails, a downwardly directed flange on each long side of said under-frame said flange having two pairs of slots upwardly extending from the lower edge of said flange and forming at the upper end one half of an axle bearing the slots of the one pair being spaced at other distance and being of other height than the slots of the other pair, a 5
